UNITED STATES PATENT OFFICE.

PETER EKMAN, OF GREELEY, COLORADO.

GRINDSTONE ATTACHMENT.

1,178,002.

Specification of Letters Patent. Patented Apr. 4, 1916.

Application filed November 24, 1915. Serial No. 63,272.

To all whom it may concern:

Be it known that I, PETER EKMAN, a citizen of the United States, residing at Greeley, in the county of Weld, State of Colorado, have invented a new and useful Grindstone Attachment; and I do hereby declare the following to be a full, clear, and exact description of the invention, such as will enable others skilled in the art to which it applies to make and use the same.

This invention relates to an improved grindstone attachment, and aims to provide a tool holder, that is capable of adjustment, so that the tool may be held in order to accommodate itself to different sized grindstones, and also permit the operator to move the tool vertically and laterally in opposite directions.

Another object of the invention is to provide a frame having an angular arm consisting of adjustable sections so that the tool may be held upon various angles, while grinding the same. The sections of the arm are provided with means adapted to be set up or adjusted for holding the sections in different positions.

In practical fields the details of construction may necessitate alterations, falling within the scope of what is claimed.

The invention comprises further features and combination of parts, as hereinafter set forth, shown in the drawings and claimed.

In the drawings: Figure 1 is a view in perspective of a grindstone frame and the grindstone therein, showing the grindstone attachment or tool holder as applied. Fig. 2 is an enlarged detail sectional view of a portion of the angular sectional arm, showing the ball and socket or universal joint between the tool clamp and one of the sections of said arm. Fig. 3 is a view partly in elevation and partly in section of the frame for supporting said sectional angular arm.

Referring more especially to the drawings, 1 designates the grindstone frame having supporting legs 2, and the grindstone 3 mounted upon the shaft 4, which is in turn mounted in bearings 5 on the frame. One end of the shaft 4 is provided with a crank 50 and handle 6, whereby revoluble movement may be imparted to the shaft and grindstone. A rectangular frame 7 is provided consisting of the tubular bars 8, 9, 10, and 11. The lower end of the tube 9 and one end of the tube 10 are connected by the elbow 12. The upper end of the tube 9 and one end of

the tube 8 are connected by the T-union 13. The upper end of the tube 11 and one end of the tube 8 are connected by the elbow 14, whereas the lower end of the tube 11 and the end 15 of the tube 10 are connected by the T-union 16. A plate 17 is secured by screws 18 to the upper face of one corner of the frame 1. This plate 17 has an upwardly extending projection 19, which extends into the T-union 16, so as to swivelly mount the rectangular frame 7. However, by setting up on the thumb screw 20, the T-union 16 may be adjustably tightened on the projection 19, so as to hold the frame 7 in adjusted fixed positions.

An angular arm 21 is provided, which consists of two sections 22 and 23. One end of the section 22 has a head 24, and surrounding the head to the collar or sleeve 25, which has threaded connections with the threaded enlargement 26 of the section 23, so that by screwing up on the sleeve or collar 25, the head 24 may be clamped against the threaded enlargement 26, so as to hold the sections 22 and 23 in adjusted positions. The section 21 consists of the parts 27, 28 and 29, which are joined by the elbows 30 and 31, so that the part 29 will extend from the part 28 in a plane vertically at right angles to the horizontal plane of the part 27. The part 29 of the section 21 of said angular arm telescopically fits into the T-union 13 so that it may be moved swivelly, thereby permitting the angular arm to swivel upon the frame 7, which in turn may swivel upon the projection 19. By setting up or tightening the thumb screw 32, the part 29 may be held tight and against movement in the T-union 13, thereby holding the angular arm in adjusted positions. The section 23 at one end terminates in an integral angular plate 33, upon one face of which a partial spherical depression, pocket or bearing 34 is formed. A plate 35 is secured to the enlarged end 36 of the plate 33 by the set screw 37. The plate 35 upon one face has a pair of pins 38 engaging the recesses or bores 39, so as to hold the plate 35 registered with the plate 33. The inner face of the plate 35 has a partial spherical bearing or depression 40, which is directly opposite the depression or bearing 34, so that the two bearings will coöperate against the opposite portions of the ball or spherical member 41 of the shank 42 of the tool clamp 43. The plates 33 and 35 are drawn tight against

each other by the set screw 37 sufficiently to hold the ball or spherical member in position, yet allow the ball or spherical member to move universally. The clamp 43 5 consists of the two parts 44 and 45 secured together by the set screw 46, so as to hold the tool, more especially a sickle or scythe blade 47 in the angular recess 48 of the part 44, so as to allow the cutting edge to be held 10 in the proper position adjacent the grinding surface of the grindstone. It is to be noted that the blade clamp may be moved universally, for instance vertically and laterally, so that the tool blade may be moved 15 to different angles relative to the grinding surface. Furthermore, the angular arm may be adjusted toward and from the grindstone, on its swivel connection in the T-union 13, or the frame 7 may be adjusted 20 swivelly upon the projection 19, so that the entire angular arm and the clamp may be moved toward and from the grinding surface of the grindstone. Furthermore, the section 23 of the angular arm may be adjusted swivelly, so as to change the angle of 25 the cutting blade or tool.

Copies of this patent may be obtained for five cents each, by addressing the "Commissioner of Patents, Washington, D. C."

The invention having been set forth, what is claimed as new and useful is:

In combination, a tubular frame supported upon a grindstone frame, an angular arm supported to move horizontally on the tubular frame, said angular arm consisting of two sections having adjustable swiveled axial connection, one of said sections terminating in a plate having a spherical bearing in one face, a second plate clamped to the first plate and having a spherical bearing opposite the first bearing, and a tool clamp having a shank provided with a spherical member or bore at one end seated 35 in said spherical bearings, whereby the tool may be moved vertically and horizontally relative to the grinding surface of the grindstone.

In testimony whereof I have signed my 40 name to this specification in the presence of two subscribing witnesses.

PETER EKMAN.
